SAFETY RIVET SET

William R. Lawler, Burbank, Calif.

Application August 6, 1943, Serial No. 497,661

1 Claim. (Cl. 279—19.5)

This invention relates to pneumatic riveting guns, and more particularly to the rivet sets thereof.

By way of illustration, it might be stated that frequently the triggers of rivet setting guns are accidentally operated while the gun is being carried from one job to another, with the result that the rivet sets of the guns are shot from the barrels of the guns, causing damage to valuable property, and frequently injuring fellow workers or persons in range of the projected rivet set.

It is therefore the primary object of the present invention, to provide means to eliminate the danger caused by the rivet sets being accidentally discharged or projected from their guns in which they are mounted.

An important object of the invention is to provide means mounted on the rivet sets of pneumatic riveting guns, which will grip the barrels of the guns to restrict movement of the rivet sets, beyond a predetermined point.

With the foregoing and other objects in view which will appear as the description proceeds, the invention consists of certain novel details of construction and combinations of parts herein-after more fully described and pointed out in the claim, it being understood that changes may be made in the construction and arrangement of parts without departing from the spirit of the invention as claimed.

Referring to the drawing:

Figure 1 is an elevational view partly in section, illustrating a pneumatic rivet setting gun, wherein the rivet set is equipped with a retaining device, constructed in accordance with the invention.

Figure 2 is a sectional view through the barrel of a rivet setting gun, the rivet set being shown in elevation.

Figure 3 is a sectional view taken on line 3—3 of Fig. 1.

Figure 4 is a sectional view taken on line 4—4 of Fig. 1.

Referring to the drawing in detail, the handle of a rivet setting gun is indicated by the reference character 5, the handle being of the usual and well known construction, and supplied with the usual trigger 6 by means of which the gun is operated.

The barrel of the gun is indicated by the reference character 7 and as shown, is provided

with shallow grooves 8 disposed adjacent to the outer end thereof. These grooves 8 provide shoulders 9 against which the springs 10 may engage. The springs 10 are secured to the rivet set, which is indicated by the reference character 11, the rivet set being formed with a recess opposite to each spring 10 to receive the curved portion 12 thereof. These curved portions 12 of the springs are so designed that spaces will be provided between the inner edges thereof and the bottoms of the recesses, as clearly shown by Fig. 1 of the drawing. These spaces, permit the springs to press inwardly so that the shoulders 9 may be cleared, should it be desired to remove the rivet set 11.

Mounted on the outer end of the rivet set, is a rubber cushioning head 14, which is formed with a depression to accommodate the head of the rivet which is being inserted or positioned in an opening.

From the foregoing it will be seen that due to the construction shown and described, should the trigger 6 be accidentally operated while the gun is being carried from one job to another, the rivet set 11 will be held against outward movement, beyond a predetermined point, by the contact of the springs 10 with the shoulders 9.

Knobs or finger pieces indicated at 13 are provided on the free ends of the springs, to afford convenience in operating the springs to press them inwardly, when the rivet set is to be released or removed from the gun barrel.

What is claimed is:

In a rivet setting gun, a gun barrel having internal longitudinal grooves formed at the open end thereof, said grooves presenting shoulders at the outer end of the barrel, a rivet set movable within the end of the gun barrel and having longitudinal grooves, the latter grooves having inwardly curved portions, spring members secured within the grooves, the free ends of the spring members being curved to fit within the curved portions of the grooves of the rivet set, portions of the curved portions of the spring members adapted to contact the shoulders holding the rivet set within the gun barrel, the free ends of the spring members extending beyond the open end of the gun barrel and adapted to be depressed to disengage the shoulders whereby the rivet set may be disconnected from the gun barrel.

WILLIAM R. LAWLER.
